CLAIM

The ornamental design for a speaker box, as shown and described.

DESCRIPTION

FIG. 1 is a rear, left and bottom perspective view of a speaker box, showing my new design;

FIG. 2 is a front, top and left perspective view thereof;

FIG. 3 is a front elevational view thereof;

FIG. 4 is a rear elevational view thereof;

FIG. 5 is a left side view thereof;

FIG. 6 is a right side view thereof;

FIG. 7 top plan view thereof;

FIG. 8 is a bottom plan view thereof;

FIG. 9 is a rear, right and top perspective view thereof;

FIG. 10 is an enlarged view of the selected portion 10 in FIG. 1;

FIG. 11 is an enlarged view of the selected portion 11 in FIG. 1;

FIG. 12 is an enlarged view of the selected portion 12 in FIG. 3; and,

FIG. 13 is an enlarged view of the selected portion 13 in FIG. 3.

The broken lines in FIGS. 1, 3 and 10-13 shown encircling the enlarged detail views are for annotative purposes only, while all other broken lines are included for the purpose of illustrating portions of the speaker box; the broken lines form no part of the claimed design.
